(57) **CLAIM**

The ornamental design for illuminated latch indicator assembly, as shown and described.

DESCRIPTION

FIG. 1 is a perspective view of an illuminated latch indicator assembly embodying our new design;

FIG. 2 is a front elevational view thereof;

FIG. 3 is an end elevational view thereof;

FIG. 4 is a cross sectional view taken on line 4—4 of FIG. 2; and,

FIG. 5 is a side elevational view of FIG. 1.

The broken line showing is for illustrative purposes only and forms no part of the claimed design.
